UNITED STATES PATENT OFFICE.

GEORGE W. PINE, OF TROY, NEW YORK.

STAYING-PIECE FOR GARMENTS.

SPECIFICATION forming part of Letters Patent No. 298,401, dated May 13, 1884.

Application filed January 31, 1884. (No model.)

To all whom it may concern:

Be it known that I, GEORGE W. PINE, of the city of Troy, county of Rensselaer, State of New York, have invented a new and useful

5 Improvement in Combined Button-Laps and Staying-Pieces for Garment Slit-Openings, of which the following is a specification.

My invention relates to that class of attachments made to garment slit-openings, and 10 more particularly to the back openings and sleeve side openings of shirts, the purposes of which are to produce an overlap or fly for button-connection and to stay the bottom of the slit-opening, so as to prevent its being 15 torn thereat.

One feature of my invention consists, as will be more fully detailed hereinafter, in the combination, with the usual form of slit-opening made in garments to produce a fly-opening 20 for button attachment, of a cross-slit made at the bottom of the usual slit and at right angles thereto, for the frontward passage of the longitudinally-folded outer and inner facing of the under lap to be connected to and with 25 the inner facing of the overlap.

My invention also consists in the combination, with the usual form of slit-opening for producing a button-fly lap, of a transverse slit made at the bottom of and at right angles to 30 the former, two plackets or pieces of fabric, each of the same size and rectangular form, and of a sufficient width, when folded longitudinally, to produce from one of them the overlap and from the other the underlap, and 35 each of them having a sufficient length to subtend the transverse slit, with the placket forming the underlap, after having been folded longitudinally and attached on one side (its edge being turned in) to one side of the vertical slit, and the turned-in edge of its other side to the garment exterior, and then passed 40 frontwardly through the transverse slit, to be sewed to the upper edge of the latter, and the inner face of the overlap, with the placket 45 forming the overlap, after having been folded longitudinally, and on the turned-in edge of one side sewed to one side of the vertical slit, and on the turned-in edge of the other side sewed to the garment exterior, with its subtending end sewed to the lower edge of the transverse slit and garment exterior.

Accompanying this specification, and form-

ing a part of it, there are three sheets of drawings, containing seven figures illustrating my invention, with the same designation of parts 55 by letter-reference used in all of them.

Of these illustrations, Figure 1 shows a part of a shirt-back containing the usual form of vertical slit, and also a transverse slit made in the fabric at the bottom of the vertical slit. 60 This figure also shows the two plackets and their rectangular form, they being shown as attached on one of their side edges to one side of the vertical slit, and as turned up at their ends, to better illustrate the position of the 65 transverse slit. Fig. 2 illustrates the position of the two plackets after having each been folded longitudinally, with the turned-in edge of one side of each placket attached to one side of the vertical slit, and that one of the 70 plackets forming the underlap is shown as passed frontwardly and through the transverse slit, preparatory to sewing it to the latter and the inner facing of the overlap. Fig. 3 shows in a reversed position of the parts 75 the attachment of the turned-up end of the underlap to the inner facing of the overlap and shirt-back after the longitudinally-folded underlap has been passed through the transverse slit, as indicated at Fig. 2. Fig. 4 illustrates the same parts and their position as 80 indicated at Fig. 3, but with the overlap folded over and down longitudinally, with its edge turned in and exteriorly sewed to the garment, and with its facings on the outer edge 85 of its fly-fold sewed together throughout their length, and so as to attach the coincident edge of the turned-up end of the underlap. Fig. 5 shows a back view of the connected parts. Fig. 6 is a front view of the attachment as 90 completed, with the button-fly or overlap and the underlap opened out to show their position. Fig. 7 illustrates a section taken horizontally on the line $x-x$ of Fig. 6, but with the underlap beneath the overlap, and not with 95 them spread apart, as in said Fig. 6. In Figs. 3, 4, and 5 the length of the parts is shown as reduced for convenience in illustration.

The several parts of the attachment are designated by letter-reference, and the process 100 steps by which they are connected are detailed as follows:

The letters $A' A^2$ indicate two plackets of equal size, and having the same rectangular

form, the one designated at A' being applied to produce, when folded and connected, the button-fly or overlap, and that indicated at A² to form the underlap.

- 5 The letter D designates a part of the shirt-back or garment, and O a vertical slit made therein, of which c' c² are its side edges; and T indicates a transverse slit made in the shirt or garment at the bottom of the vertical slit.
- 10 Both of the plackets are folded longitudinally at d, after having been each sewed to one edge of the vertical slit, as shown at S' in Fig. 1, and the other vertical edges of each placket are turned in where attached to the fabric exterior away from the slit edge, as designated at S².

The overlap as produced from the placket A' is indicated at L', and the underlap as made from the placket A² is designated at L². To 20 make the latter, the placket A², after having been sewed to the edge c² of the vertical slit, is folded over and down on the fold-line d, and on its turned-in outer edge is attached to the garment exterior above the transverse 25 slit, as indicated at S², and also to the upper edge of the latter at S³, and is then passed forwardly through said transverse slit, turned up, and at S⁴ sewed to the inner facing-fold of the overlap before the longitudinal fold at d has been laid, and before the exterior facing of the overlap has been on its outer edge sewed to the garment.

At Fig. 4 the frontwardly-passed folded placket A² of the underlap, where turned up at the end, is shown as sewed on its edges to the inner facing of the overlap, and to the garment where subtending the latter horizontally, and as cross-sewed to the lower edge of the transverse slit at at S⁵.

40 The overlap L', as produced from the placket A', is shown at Fig. 1 with the edge of the placket attached to the edge c' of the vertical slit, and at Fig. 2 as folded over and down on the line of such union, and then folded longitudinally on the fold-line d. After the lower 45 end of the underlap has been passed through the transverse slit, turned up, and attached to the inner facing-fold of said overlap, as shown at Figs. 4 and 5, then the outer edge 50 of the placket A', thus forming the overlap, is sewed to the garment exterior. The placket is also sewed horizontally to the lower edge

of the transverse slit at S⁵, and border sewed to the garment below the slit, as indicated at a'. The fly-edges of both the overlap and underlap where folded at d d, are sewed together, as designated at m' m².

A combined button-lap and stay thus made and attached has the advantage of a strong crotch-stay, produced from the frontwardly- 60 passed and turned-up end of the placket forming the underlap, and which accumulation of material, where thus desirable, I am able to apply by the intervention of the cross-slit at the bottom of the vertical slit. 65

Having thus described my invention, what I claim, and desire to secure by Letters Patent, is—

1. In a combined button-lap and stay for garment-slit openings, the combination of a 70 cross-slit made in the garment below the vertical slit-opening, an overlap attached to one side of the garment above the cross-slit, an underlap attached to the other side of the garment-slit above the cross-slit, with the underlap sewed to the upper edge of the cross-slit, and its lower end passed frontwardly 75 through said cross-slit, turned up, and sewed to the inner facing of the overlap, and the latter sewed to the lower edge of the cross-slit, 80 as shown and described.

2. In a combined button-lap and stay for garment-slit openings, the combination of the cross-slit T at the bottom of the slit O, the plackets A' A², each attached, as shown, up- 85 on one of their side edges to one of the opposite sides of said slit O, and each folded longitudinally and attached on their other sides to the garment exterior above the cross-slit, with the folded placket A², attached to the 90 upper edge of said cross-slit, passed frontwardly through the latter, turned up, and sewed to the inner facing of the placket A', and the latter sewed to the lower edge of the cross-slit and the garment exterior, below the 95 latter, as shown and described.

Signed at the city of Troy, New York, this 18th day of January, 1884, and in our presence whose names were hereto by us written.

GEORGE W. PINE.
